COMBINED KEY RING AND MATCHBOOK HOLDER

Julian Holland, 780 Wellington Ave., Cranston, R.I.

Filed Dec. 23, 1963, Ser. No. 77,900

Term of patent 7 years

(Cl. D17—14)

FIG. 1 is a front elevational view of a combined key ring and matchbook holder showing my new design;

FIG. 2 is an edge view thereof taken from the right-hand side of FIG. 1;

FIG. 3 is a rear elevational view thereof;

FIG. 4 is a section taken on line 4—4 of FIG. 3; and

FIG. 5 is a section taken on line 5—5 of FIG. 3.

I claim:

The ornamental design for a combined key ring and matchbook holder, substantially as shown.
